FEEDING APPARATUS

Filed Sept. 30, 1929

FIG. 1.

FIG. 2.

INVENTOR
ALBERT MUTSCHLER
BY
Eric Dachinger.
ATTORNEY

UNITED STATES PATENT OFFICE

ALBERT MUTSCHLER, OF ROCHESTER, NEW YORK, ASSIGNOR TO A & H G MUTSCHLER INC., OF ROCHESTER, NEW YORK, A CORPORATION OF NEW YORK

FEEDING APPARATUS

Application filed September 30, 1929. Serial No. 396,138.

This invention relates to material feeding means for punch presses and has for its object to provide a feeding apparatus having a yielding drive which will prevent any part 5 of the apparatus from being damaged when the material fed by the apparatus jams and prevents the proper working thereof.

This and other objects of this invention will be apparent from the drawings, the 10 specification and the appended claims forming a part thereof.

In the accompanying drawings:

Figure 1 is a vertical sectional view of the feeding apparatus as it appears when mounted 15 on a punch press.

Figure 2 is a top plan view of the feeding apparatus without the punch press.

Figure 3 is a vertical sectional view of the push rod and guide of the feeding apparatus, 20 the section being taken on the line 3x—3x of Figure 1.

In the several figures of the drawings like reference numerals indicate like parts.

The feeding apparatus forming the subject 25 matter of my present invention is suitable for feeding stock for both blanking and forming operations. In the form illustrated in the figures of the drawings the apparatus is adapted for feeding circular blanks or discs 30 to the die of the punch press to be perforated thereby. With slight modifications and adjustments the same apparatus however can be adapted to feed other material either for blanking or forming in the die 35 of the punch press and the scope of the invention is therefore not limited by the particular detail design of the apparatus illustrated in the drawings.

The feeding apparatus is supported on the 40 die block 1 and projects to one side thereof. In the die block is mounted the die 2 with which the punch 3 cooperates to perforate the discs or blanks fed by the feeding apparatus. The punch 3 is mounted in the bottom of the ram 4 and is reciprocated thereby on the 45 movement of the ram between the gibs 5 and 6 on the operation of the punch press.

A base plate 7 is suitably fastened to the die block 1 and on it are mounted the brackets 8 and 9. Bracket 8 provides the support

for the cylindrical magazine 10 from which the blanks or discs are fed to the die. Both the top and bottom of the magazine are open and the lower end is located above the runway 11 so that the lowermost blank or disc 55 in the magazine is allowed to rest thereon. The runway 11 extends from the magazine toward the die 2 and the wall of the magazine is cut away over the runway to permit the lowermost blank or disc resting thereon 60 within the magazine to be pushed from under the magazine and placed over the die 2. This is done by the push rod or slide 12 which is mounted in the guide channel 65 formed between the guides 13 and 14 at the left of the magazine. The central portion of the push rod or slide is slotted and into this slot engages the free end of the bell crank lever 15. The outer end of the push rod or slide 12 is provided with an extension 16 which is adjustably fastened thereto by means of the screws 17 and 18. These screws pass thru slots in the extension 16 so as to permit this extension to be adjusted laterally on the end of the push rod or slide 12. The 70 inner end of the extension 16 is provided with a lug 19 which projects into the slot of the push rod and forms the stop against which the bell crank lever 15 is held by the spring 20. This spring is attached with one 75 end to the bell crank lever 15 and with the other end to the eye 21 depending from the outer end of the push rod extension 16 so that the tension of the spring 20 normally holds the free end of the bell crank against the lug 80 85 19 in the slot of the push rod.

The bell crank is operated by the ram 4 of the punch press by means of the arm 21 which is attached thereto and projects to one side thereof. A link 22 connects the arm 21 90 with the bell crank and is pivoted with one end to the arm and with the other end to the bell crank 23. On the reciprocation of the ram of the punch press the bell crank is thus oscillated by the reciprocating movement of 95 the ram on the operation of the punch press. The bell crank in turn operates to move the slide or push rod 12 back and forth in its guide channel so that the front end thereof, which passes under the magazine 10, pushes 100

the lowermost of the discs from under the magazine along the runway 11 until it reaches a point above the die 2 where the runway is cut away to allow the disc to drop down onto the die in position to have the punch 3 perforate it on its descent. As will be seen from Figure 1 the connection between the ram and the push rod or slide is such as to cause the slide or push rod to move toward the die and deliver a disc to the die on the up stroke of the ram and move away from the die on the down stroke of the ram while the delivered disc is perforated by the punch carried by the ram.

If for any reason one of the discs in the magazine cannot be pushed out from under it or jams in the runway leading from the magazine so that the push rod or slide cannot complete a movement corresponding to the movement of the ram, the yielding connection between the bell crank 15 and the push rod or slide 16, which is formed by the spring 20, allows the bell crank to swing in the slotted section of the push rod without moving the push rod in the guide slot. The yielding connection thus prevents the breaking of any part of the driving connection between the ram and the push rod on the sudden arrest of the movement of the push rod due to the jamming of the discs while being fed from the magazine to the die. The bell crank will continue to swing in the slot of the push rod on the operation of the punch press as long as the push rod is held against movement but no harm will be done to the mechanism of either the punch press or the feeding apparatus so that after the cause of the jamming of the disc is corrected the feeding apparatus will be ready to again feed the discs from the magazine to the die.

In order to properly position the blanks or discs over the die a stop mechanism is provided. This stop mechanism comprises a lever 30 which is pivoted on one side of the runway and carries the pins 31 and 32, one at each end thereof. A spring 33 is attached to the outer end of the lever 30 and yieldingly holds this end of the lever so that the pin 31 is held in place in the notch 34 provided in the side of the runway. In this position the pin offers no obstruction to the passage of the discs or blanks in the runway. While the pin 32 is held nested in the notch 34 the pin 31, carried at the other end of the lever 30, is held to project into the runway or guide channel of the push rod or slide 12, but when the slide or push rod is moved and reaches the pin 31, the pin is forced into the groove in the side of the runway and in doing so rocks the lever 30 and swings the pin 32 out from its notch into the dotted line position illustrated in Figure 2. In this position the pin 32 serves as a stop for the disc or blank which is fed forward by the push rod or slide and stops the disc or blank when it is located

over the die as illustrated in dotted lines in Figure 2. The sides of the ends of the runway are cut away so as to allow the blank or disc to drop down on top of the die when it has reached this position. The blank or disc is then ready to be operated upon by the punch 3 which operation takes place on the return movement of the push rod or slide 12 as illustrated in Figure 1. After the outer end of the slide or push rod has passed the pin 31 on its return movement to the magazine the spring 33 again operates to swing the lever 30 back to its normal position in which the pin 31 is swung out into the guide channel of the slide or push rod while the pin 32 is swung back into the groove 34 in the side of the runway. This is necessary in order to withdraw the stop and allow the perforated disc or blank to be pushed away from the die by the push rod extension 35. This extension projects forwardly from the bottom of the push rod or slide and is thin so as not to interfere with the action of the end of the push rod against the discs or blanks located in the magazine. The extension 36 projects forwardly of the push rod or slide a distance which brings the outer end of the extension in engagement with the perforated disc or blank and pushes it out of the way before the next disc or blank is fed to the die and is located thereon by the push rod proper.

I claim:

1. In a feeding apparatus for punch presses the combination of a guide, a push rod having a slot therein mounted to reciprocate in said guide, an oscillating lever engaging into the slot in said push rod and adapted to swing back and forth therein, a spring connecting said lever with said push rod to yieldingly hold said oscillating lever against one end of the slot in said push rod and reciprocate said push rod on the oscillation of said lever by means of said connecting spring, said push rod being adapted to feed a blank on the movement thereof in one direction.

2. In a feeding apparatus for punch presses the combination of a guide, a push rod having a slot therein mounted to reciprocate in said guide, an adjustable stop at one end of the slot, an oscillating lever extending into the slot in said push rod, yielding means connecting said lever with said push rod and holding said lever against said adjustable stop in said slot, means for oscillating said lever on the operation of the punch press to feed blanks to the die of the punch press.

3. In a feeding apparatus for punch presses the combination of a guide, a runway forming a continuation of said guide, a push rod mounted to reciprocate in said guide, said push rod having a slot therein, a magazine adapted to hold blanks mounted above said runway, an operating lever engaging the slot in said push rod and adapted to swing back and forth therein, yielding means con-

necting said operating lever with said push rod to hold said push rod against one end of the slot and move said push rod thru said yielding means in one direction, said push rod being adapted to feed a blank from said magazine along said runway.

4. In a feeding apparatus for punch presses the combination of a guide, a runway forming a continuation of said guide, a push rod mounted to reciprocate in said guide, a magazine adapted to hold blanks mounted above said runway, an operating lever for said push rod, yielding means connecting said operating lever with said push rod to move said push rod thru said yielding means in one direction, said push rod being adapted to feed a blank from said magazine along said runway, a stop mechanism comprising a lever, a pin carried at one end of said lever adapted to project into the path of said push rod, a stop pin carried at the opposite end of said lever, said first pin being operated by said push rod to swing said stop pin into said runway and provide a stop for the blank fed by said push rod on its movement in one direction.

5. In a feeding apparatus for punch presses the combination of a guide, a runway forming a continuation of said guide, a push rod mounted to reciprocate in said guide, a magazine adapted to hold blanks mounted above said runway, an operating lever for said push rod, yielding means connecting said operating lever with said push rod to move said push rod thru said yielding means in one direction, said push rod being adapted to feed a blank from said magazine along said runway, a stop mechanism comprising a lever, a pin carried at one end of said lever adapted to project into the path of said push rod, a stop pin carried at the opposite end of said lever, said first pin being operated by said push rod to swing said stop pin into said runway and provide a stop for the blank fed by said push rod on its movement in one direction and means for withdrawing said stop pin from the blank on the return movement of said push rod to permit the blank after being operated upon to be moved out of said runway to make room for the next blank fed by said push rod.

In testimony whereof I affix my signature.
ALBERT MUTSCHLER.
